FIG. 5

UNITED STATES PATENT OFFICE.

CHARLES DE LUKACSEVICS, OF NEW YORK, N. Y., ASSIGNOR, BY MESNE ASSIGNMENTS,
TO EDMUND LOFFLER, OF NEW YORK, N. Y.

CARBURETER.

1,255,716.

Specification of Letters Patent.

Patented Feb. 5, 1918.

Application filed December 6, 1916. Serial No. 135,444.

To all whom it may concern:

Be it known that I, CHARLES DE LUKACSEVICS, a citizen of the United States, residing at New York, in the county of New York and State of New York, have invented new and useful Improvements in Carbureters, of which the following is a specification.

This invention relates to improvements in carbureters for internal combustion engines.

The principal objects of the invention are to provide a carbureter which is especially adapted for high speed engines; whose action shall be automatically controlled by the suction of the engine; and wherein the fuel is delivered from the nozzle in consequence of the movement of the main air stream past said nozzle, and the amount of air admitted is directly controlled by a suitably balanced valve which is sensitively responsive to the suction influence within the mixing or carbureting chamber and is not subject to fluttering.

The invention consists in certain features of structure, combination and relation which will appear more in detail as the description proceeds.

Embodiments of the invention are illustrated in the accompanying drawings, wherein:

Figure 1 is a vertical longitudinal sectional view of a carbureter in which the features of the invention are incorporated;

Fig. 2 is a detail plan view showing certain structural elements of the carbureter, certain other elements being omitted to promote clearness of illustration;

Fig. 3 is a view showing in plan and side elevation the inner fuel discharge member;

Fig. 4 is a view showing a plan and side elevation of the outer fuel discharge member;

Fig. 5 is a view showing in plan and vertical section an oil well which forms a part of the nozzle and which furnishes support for the fuel discharge members;

Fig. 6 is a vertical longitudinal sectional view showing a slightly modified construction; and

Fig. 7 is a horizontal sectional view on the line 7-7 of Fig. 6.

Similar characters of reference designate corresponding parts throughout the several views.

Referring to Figs. 1-5;

The casing of the carbureter provides a carbureter chamber 1 in which fuel is delivered from a nozzle designated generally as 2 and air is delivered from a supply pipe 3, which, if desired, may be provided with an air-heating medium (not shown), or may, for the purpose of heating the air, extend in suitable relation to the engine exhaust system (not shown).

As shown, the pipe 3 opens into an air inlet chamber 4 having a partition 5 which provides a seat for an automatically operating air valve 6 by which the admission of air into the carbureting chamber is controlled for all normal ranges of speed. The pipe 3 may, if desired, be provided with a butterfly or equivalent valve 7 by which an initial adjustment of the air supply may be made. The valve 6 is urged toward its seat by a spring 8 which, at a certain low speed, will effect the closure of said valve; and for the purpose of enabling the engine to be run at low or throttling speed when the valve 6 is closed, the partition 5 has formed therein slots 9 providing for the admission of a small amount of air to the carbureting chamber. If desired, the slots 9 may be controlled by a regulating valve 10, which, as shown, is in the form of a flat ring with its seating on the upper face of the partition 5 and is provided with slots 11 adapted by a pivotal adjustment of the ring 10 about its center to be brought more or less into registry with the slots 9, the valve 10 thereby regulating the effective size of the slots 9. For the purpose of enabling a rotatable adjustment of the valve 10 as described, said valve carries a suitably located upright post 12 having at its upper end a lateral projection which extends through a slot 13 in the carbureter casing and carries, externally of said casing, a securing nut 14 (Fig. 7) having formed therewith a flange 15 which provides a closure for the slot 13. Obviously, when the nut 14 is tightened, the valve 10 will be held against movement, and when the nut 14 is backed off, the valve 10 may be adjusted to any position desired for the purpose of regulating, *i. e.*, increasing or decreasing, the amount of air admitted into the carbureting chamber for maintaining the operation of the engine at low or throttling speed.

The nozzle 2 is arranged in upright relation centrally and axially of the carburetor casing and is supported by a pipe or tube 16 which extends transversely through the casing and leads from any suitable source of fuel supply, for example, and as is preferred, a fuel chamber 17 (Fig. 6) carried by the carburetor casing and equipped with conventional float feed mechanism 18 for maintaining a constant level and a strainer 19 for preventing the passage of solid particles into the pipe or tube 16.

The nozzle has, as a functional part thereof, a well 20 (Fig. 5), which, as shown, is separable from the tube 16 and has at its lower end a threaded projection 21 for engagement with an internally-threaded boss 22 formed with said tube. The nozzle also includes an outer fuel discharge member 23 and an inner fuel discharge member 24. The member 23 is of slightly less depth than the well 20 in which it is positioned. Said member is formed with a cylindrical body portion and with an enlarged circumscribing rib 25 at its upper end, said rib having a triangular cross-section. The member 23 has its outer face provided with discharge ducts or grooves 26 which extend from its lower end in parallel relation throughout its cylindrical portion and in radial diverging relation along the under face of the rib 25, terminating at the apex of said rib. The well 20 has at its upper end a bell or flaring mouth 27 by which the outer fuel discharge member 23 is supported by and within said well, the rib 25 of said member engaging upon the bell or flaring mouth 27 and the upper or discharge ends of the ducts or grooves 26 lying just beyond the upper edge of the mouth 27. The member 23 has a close fit within the well 20 whereby the liquid fuel will flow only through the ducts or grooves 26.

The outer fuel discharge member 23 is of cupped construction and is provided at its lower end with a base 28 to furnish support for the inner fuel discharge member 24 which sets or nests within the outer member and has a close fit within the same. The inner fuel discharge member 24 is of cylindrical outline and is provided on its outer face with parallel fuel discharge grooves or ducts 29 which terminate at or immediately beyond the upper edge of the member 23, the base 28 of the latter having a central opening 30, and having its upper face provided with an annular channel 30^a and with radial ducts or grooves 30^b extending between the opening 30 and the channel 30^a, through which central opening, radial grooves and annular channel the fuel in the well 20 flows to the ducts 29. It is preferred that the upper edge of the member 23 shall be inclined whereby the several ducts 29 shall have their discharge points at different elevations, all,

however, above the common plane wherein the discharge terminals of the ducts 26 lie.

For the regulation of the velocity of the air stream which moves past the discharge end of the nozzle 2, it is preferred to provide a Venturi ring 31 which has a close sliding fit within the chamber 1 and is connected to the main air valve 6 for operation thereby by rods 32 arranged at appropriate intervals.

The carbureting chamber 1 is open to the motor suction tube and the volume of fuel passed to the engine is controlled by a throttle valve 33 of butterfly or other suitable type which is preferably located at the upper end of the carbureting chamber.

The valve 6 is responsive to the prevailing suction influence in the carbureting chamber throughout a certain normal range of speeds and, therefore, has a normal rising and falling action in the course of which it increases or decreases the amount of air admitted into the carbureting chamber from the air inlet chamber 4. In order to prevent the valve 6 from seating too suddenly or with a shock in the event of a sudden and pronounced drop in the prevailing suction influence,—in other words, to prevent fluttering—said valve has formed therewith a central axial extension 34 which at its lower end carries a plunger head 34^a for operation with dash-pot effect in a suitable chamber 35 formed in the base of the carburetor casing and having a bottom cap-closure 35^a.

The strength of the spring 8 may be regulated as desired by suitable means. As shown in Figs. 1 and 2, the spring 8 bears at its lower end against the free end of a lever 36 mounted on a rock shaft 37 for which the carburetor casing is formed with a bearing 38. The shaft 37 projects through said bearing beyond the casing and at its outer end carries an arm 39 which is engaged by an adjusting screw 40 threaded in a bracket 41 which is secured to or formed with the carburetor casing.

In the organization of the carburetor, the casing thereof is made in four sections. The lowest section provides the air inlet chamber 4 and has a seating against the under face of the adjacent section which carries the nozzle supply pipe or tube 16. The section which provides the wall of the carbureting chamber and within which the Venturi ring 31 has a close sliding fit, has its seating against the section next below which, as stated, carries the tube 16 and the uppermost section which is formed with the flange 42 to provide for the attachment of the carburetor on the motor suction tube. The said uppermost section is formed with a spider 43 which projects into the carbureting chamber and receives the thrust of an upper securing nut 44. The sections, related as described, are held or clamped together by

an upright central stem 45, secured in the pipe or tube 16 and carrying the upper securing nut 44 and a depending stem 45^a formed integral with or secured to the pipe 5 or tube 16 and carrying the securing nut 46 on its lower end, the nut 46 bearing against the base 35^a of the dash-pot chamber 35. The stems 45 and 45^a are, functionally, a single stem and, if desired, may be integrally connected and threaded in a central opening piercing the pipe or tube 16 as shown in Fig. 6. The stem 45^a projects through the valve spring 8, said spring at its lower end being seated within the plunger 34.

The fuel discharge members 23 and 24 are secured in operative relation by a pair of nuts 47 mounted on the stem 45. It is obvious that by removing the nuts 44 and 47 20 the carbureter may be completely dismantled and access may be had to any of its parts for the purpose of cleaning, renewal or repair.

The modified construction shown in Fig. 6 25 differs merely colorably as regards certain of its details from the construction described. Specifically, it differs in the form of the throttle valve arranged above or at the upper end of the mixing chamber, in the means 30 for adjusting the spring 8 which acts on the air valve 6 and in certain details of the construction of the carbureter casing. In lieu of the throttle valve 33 of butterfly form shown in Fig. 1, the modified construction 35 provides a horizontal valvular partition 33^a which comprises a stationary upper member 33^b cast with the upper section of the carbureter, and, incidentally, serving the function of the spider 43 in providing a bearing for 40 the upper securing nut 44 on the stem 45, and a rotatable lower member 33^c which has an annular depending apron 33^d. The apron 33^d forms a portion of the wall of the carbureting chamber and serves as a guide for 45 the Venturi ring 31. Said apron is provided with an outwardly projecting operating arm 33^e which works in a slot in the carbureter casting. The members 33^b and 33^c are formed 50 with radial slots, which, in consequence of the turning movements of the member 33^c, are brought more or less into registry for the purpose of regulating, in an obvious manner, the amount of fuel mixture passed to the motor suction tube.

55 For the adjustment of the tension of the spring 8 the stem 45, according to the modification in Fig. 6, is formed below the tube 16 with a squared portion 45^b upon which is slidably mounted a collar 48 against whose under face the spring 8 bears. Above the squared portion 45^b a collar 49 is rotatably mounted on said stem, the collars 48 and 49 having co-acting cam faces whereby a rotation of the collar 49 in one direction will 60 effect a downward movement of the collar 65

48 to increase the strength of the spring 8 and a rotation of the collar 49 in a reverse direction will permit an upward movement of the collar 48 to decrease the strength of the spring 8. The collar 49 carries a radially disposed operating arm 50 which is formed with an arcuate flange 51 projecting at opposite sides thereof and providing a closure for the slot 52 in the wall of the carbureter casing through which passes the 70 shank of the screw 53 for effecting movement of the collar 49 and for securing said collar in any desired position.

For a certain range of low speeds, the 75 gasolene will be discharged into the carbureting chamber through the ducts or grooves 26 of the outer discharge member 23. But for a range of higher speeds, the ducts or 80 grooves 29 will function in addition to the grooves 26. Where the terminals of the 85 ducts or grooves 29 are at different elevations, the number of such ducts or grooves through which gasolene is discharged will 90 depend upon the prevailing suction influence, being greater or less as the suction influence is greater or less. In this way, the amount of liquid fuel discharged by the nozzle is proportionate to the demands of the engine.

The parts of the carbureter may be made 95 of any desired materials but bakelite is of special advantage for those parts whose surfaces are in contact with the combustible mixture, for example in the embodiment of Fig. 1 it is proposed to form the body part 100 of the carbureter casing, the Venturi ring and the body part of the float feed chamber (see Fig. 6) of bakelite.

I claim as my invention:

1. In a carbureter, in combination, a casting, a fuel pipe therein and a fuel nozzle therein comprising an upright cylindrical well secured to said fuel pipe, a cylindrical outer fuel discharge member closely fitting within said well and having a circumscribing rib at its upper end which seats upon the upper surface of said well, said member being of less depth than said well and having its outer face provided with ducts which extend vertically from its lower end and terminate at the apex of said rib, said member being of cupped form, and a cylindrical inner fuel discharge member which seats and has a close fit within the outer member and has its outer surface provided with ducts which extend vertically from its lower end and terminate beyond the upper face of the outer member, the latter having its lower end formed to provide for access of the fuel in said well to the ducts of the inner member.

2. In a carbureter, in combination, a casting, a fuel pipe therein, and a fuel nozzle therein comprising an upright cylindrical well secured to said fuel pipe, a cylindrical

- outer fuel discharge member closely fitting within said well and having a circumscribing rib at its upper end which seats upon the upper surface of said well, said member being of less depth than said well and having its outer face provided with ducts which extend vertically from its lower end and terminate at the apex of said rib, said member being of cupped form and having its base 10 provided with a central opening and in its upper face with an annular groove and ducts extending between said opening and groove, and a cylindrical inner fuel discharge member which has a close fit within the outer member and seats upon the base thereof, said inner member having its outer surface provided with ducts which extend vertically from its lower end and terminate beyond the upper edge of the outer member.
- 20 3. In a carbureter, in combination, a casing, a fuel pipe therein, and a fuel nozzle therein comprising a cylindrical well secured to said fuel pipe, a cylindrical outer fuel discharge member closely fitting within said well and having a circumscribing rib at its upper end which seats upon the upper surface of said well, said member being of less depth than said well and having its upper face inclined and its outer face provided 25 with ducts which extend vertically from its lower end and terminate at the apex of said rib, said member being of cupped form, and a cylindrical inner fuel discharge member which seats and has a close fit within the outer member and has its outer surface provided with ducts which extend vertically from its lower end and terminate beyond the upper face of the outer member, the latter having its lower end formed to provide for 30 access of the fuel in said well to the ducts in the inner member.
4. In a carbureter, in combination, a casing and a fuel nozzle therein comprising as companion elements an upright cylindrical well, a cylindrical outer fuel discharge member fitting closely within and supported by said well and a cylindrical inner fuel discharge member fitting closely within and supported by said outer member, certain of
- said companion elements being formed with 50 vertical grooves extending between their lower and upper ends to provide an outer series of fuel discharge ducts between the well and the outer discharge member and an inner series of fuel discharge ducts between 55 the outer and inner discharge member, the outer discharge member having its lower end formed to provide for access of the fuel, in said well to the inner series of ducts, the ducts of the inner series terminating at points above the outer discharge member and the ducts of the outer series terminating at lower points above the well.
5. In a carbureter, in combination, a casing, an upright fuel nozzle arranged centrally thereof, the casing having an air inlet below the fuel nozzle and an annular valve seat through which air from said inlet may pass in adjacency to said nozzle, a valve 60 spring urged toward said seat and operable by engine suction, a Venturi ring having a close sliding fit within said casing and surrounding said nozzle and rods connecting said ring and said valve.
6. In a carbureter, in combination, a casing, an upright fuel nozzle arranged centrally thereof, the casing having an air inlet below the fuel nozzle and an annular valve seat through which air from said inlet may pass in adjacency to said nozzle, a valve 65 having a central axial depending recessed plunger, said valve being operable by engine suction, a head mounted on said plunger, a chamber carried by said casing within which said head operates with dashpot effect, a central stem connecting the parts of the casing and providing a guide for said valve and a spring urging said valve toward said seat, said spring surrounding said stem and fitting within the recess of said plunger.
- In testimony whereof I have hereunto set my hand in presence of two subscribing witnesses.
